UNITED STATES PATENT OFFICE.

LOUIS J. HIRT, OF BOSTON, MASSACHUSETTS, ASSIGNOR TO HARRY W. HILL, OF CLEVELAND, OHIO.

FRICITION-CLUTCH.

SPECIFICATION forming part of Letters Patent No. 429,446, dated June 3, 1890.

Application filed December 20, 1889. Serial No. 334,405. (No model.)

To all whom it may concern:

Be it known that I, LOUIS J. HIRT, a citizen of the United States, residing at Boston, in the county of Suffolk and State of Massachusetts, have invented certain new and useful Improvements in Friction-Clutches, of which the following is a full, clear, and exact description, reference being had to the accompanying drawings, in which—

10 Figure 1 is a central longitudinal sectional view of one embodiment of my improved clutch. Fig. 2 is a top view of one of the clutch-arms and the clutch mechanism connected therewith. Fig. 3 is a transverse sectional view on the line 3 3 in Fig. 1, and Fig. 15 4 is a view showing the inner end of the arms H' and a modified connection between them and the sliding sleeve.

My invention relates to that class of devices which are known as "friction-clutches," and it is designed particularly as an improvement upon that class of friction-clutches in which a pair of clutch members are mounted upon a clutch-arm and are simultaneously moved in radial paths toward and from an interposed cylindric flange for the purpose of grasping and releasing the same.

The object of my invention is to provide novel and improved mechanism for imparting to the clutch members their simultaneous inverse movement.

To this end it consists in the combination of parts herein described and shown, and pointed out definitely in the claims.

35 Referring to the parts by letters, A represents a shaft.

B represents an independently-revoluble pulley mounted concentric with said shaft, and provided with a concentric cylindric flange b.

40 C represents a clutch-frame rigidly secured to the shaft by a key a or other appropriate means. This clutch-frame is provided with as many radial arms c as it is desired to employ clutch systems—that is to say, pairs of jaws and their operating mechanism.

45 D represents the outer and D' the inner clutch member. These clutch members are of a well-known type, and consist of an inwardly-directed shank d and an overhanging jaw. The shanks d are mounted upon oppo-

site sides of the clutch-arm, and are prevented from being displaced laterally by the side flanges c', and are held against the clutch-arm by plates E and F, which are bolted to said flanges c'. A lever G passes through a slot in the clutch-arm and is pivoted to said clutch-arm by the pivot g. On opposite sides of this pivot the lever is also pivotally connected with the two jaw-shanks by the pivots g' g'. This lever G is rocked upon its pivot, and the jaws thereby simultaneously moved toward or from each other and the interposed cylindric flange b by a toggle H. The outer link h of this toggle is pivoted to some part of the clutch-arm and a lower link h' is pivoted to an extension of the lever G. An arm H', rigidly connected with the toggle-link h, extends inward toward the shaft. Its inner end is suitably connected to a sleeve J, slideable upon the shaft, whereby the toggle is straightened and the jaws closed as the sleeve is moved in one direction or bent, and the jaws thereby opened when the sleeve is moved in the opposite direction. When the central toggle-pivot passes the line connecting the two other toggle-pivots, the clutch is locked and can only be unlocked by the backward movement of the sliding sleeve.

The drawings represent two forms of connecting the arm H' with the sleeve. Fig. 1 shows this connection in the form of a link pivotally connected with the sleeve and arm. In Fig. 4 a pin on ears j j on the sleeve passes through a slot in the arm H'. I am thus able, if I desire, to get the entire clutch mechanism, including the sleeve, upon a very small part of the shaft by employing the latter construction; or the sleeve may be removed to any desired distance from the clutch mechanism by using a link of suitable length.

In clutches of this class the jaws are generally faced with wood, and by reason of the wearing away of the wood faces it is necessary, in a practical clutch, to provide means for adjusting the mechanism to compensate for this wear. The means I have provided are as follows:

e represents a lug on the outside of the clutch-arm, or specifically, as shown, a part of the plate E. This lug is provided with a

socket e' , which receives the shank k of the piece K. This piece K is provided with an ear or ears, to which is pivoted the upper end of the toggle-link h . A set-screw M enters 5 the lug e and bears against the end of the shank k , whereby the piece K may be moved inward toward the shaft as the jaws wear. In the form shown the lug e is split and provided with ears e^2 , and by means of a bolt or 10 screw e^3 , which passes through them, the shank k may be clamped sufficiently tight to prevent its slipping outward when the toggle is operated, but which will permit the screw M to crowd it outward for the purpose of adjustment.

Having thus described my invention, what I claim as new, and desire to secure by Letters Patent, is—

1. In a friction-clutch, in combination, a 20 cylindric flange, a clutch-arm, a pair of clutch members mounted thereon, a lever pivotally connected to said arm and on opposite sides of that pivot to the clutch members, respectively, a toggle the links of which are pivotally connected one to the clutch-arm and one to an extension of the said lever, and mechanism for operating said toggle, substantially as and for the purpose specified.

2. In a friction-clutch, in combination, a 30 cylindric flange, a clutch-arm, a pair of clutch members mounted thereon, a lever pivotally connected to said arm and on opposite sides of that pivot to the clutch members, respectively, a toggle, a pivot connecting the outer 35 toggle-link with the clutch-arm, a pivot connecting the inner toggle-link with said lever, an arm rigidly attached to the outer toggle-

link, a slidable sleeve, and suitable connections between said arm and sleeve, substantially as and for the purpose specified.

3. In a friction-clutch, in combination, a cylindric flange, a clutch-arm, a pair of clutch members mounted thereon, a lever pivoted to said arm and on opposite sides of said pivot with the clutch members, respectively, a toggle, a pivot connecting the inner toggle-link with said lever, a pivot connecting the outer toggle-link with the clutch-arm, mechanism for adjusting the position of this last-named pivot, and mechanism for operating said toggle, substantially as and for the purpose specified.

4. In a friction-clutch, in combination, a cylindric flange, a clutch-arm, a pair of clutch members mounted thereon, a lever pivoted to said clutch-arm and on opposite sides of this pivot with the clutch members, respectively, a lug attached to the clutch-arm and provided with a socket, a piece K, having a shank which enters said socket, mechanism 55 for holding it therein, a set-screw which screws into the outer end of said lug and bears against said shank, a toggle, a pivot connecting the inner toggle-link with said lever, a pivot connecting the outer toggle-link with the piece K, an arm rigidly secured to the outer toggle-link, a slidable sleeve, and suitable connections between said arm and sleeve, substantially as and for the purpose specified.

LOUIS J. HIRT.
